DESIGN
W. W. BACON.
LAMP

No. 12.

Patented Oct. 18, 1843

William W. Bacon, Middletown, Connecticut
Letters Patent N° 12. dated 18th Oct 1843

The Schedule referred to in these Letters Patent and Annexing part of the same: —

To all whom it may concern: —

Be it known that I William W. Bacon of Middletown in the County of Middlesex, and State of Connecticut, have invented a new Design for a Lamp for burning Lard, Fat, Tallow &c, which is described as follows: —

The nature of my invention consists in the production of a new design for a Lamp for burning Lard having tubes of copper or any other suitable material arranged in such a manner as to become self conductor

of heat, so as to cause the congealed substance to become liquid, combined with a Lamp, glass, glass holder, shade, and Reflector as hereinafter set forth and described, represented —

1st. Let these tubes be made either flat, round, or of any other desired form and of sufficient length to reach nearly to the bottom of the vessel containing the lard or other substance to be burned, but the size of them will vary according to the quantity of light required.

In ordinary lamps, the tubes should rise about one half of an inch above the top of the said vessel; and the tops of the tubes are cut off horizontally in such a manner as to have a portion of them projecting above the rest to a sufficient height, and of a sufficient size to be acted on by the flame when the Lamp is in use, so as to become sufficiently heated to melt the lard or other substance to be burned and to keep the same in a liquid state, and for this purpose, and also for the convenience of inserting and trimming the wicks, it is best to leave a portion of the top of the tubes equal to about one third thereof projecting as aforesaid about one eighth of an inch above the rest in flat tubes, and about one fourth of an inch in round tubes. The proportion, however, of this projecting part to the remainder of the tops of the tubes will necessarily be a little greater or a little less according to the form and size of the tubes.

Three parts of the tubes, which are inserted into the vessel, are made with one or more openings, one in each of which, extends, nearly, to the top of the vessel for the purpose of admitting the lard or other substance to be burned, freely to the wicks near the burning point.

I consider that the best mode of applying these tubes to the vessel is to burn them all thin, near

to each other with their said projecting parts side by side in such a position that the flames of the two wicks may be made to pass directly over the said projecting parts, and to blend together, thus forming a column of light and heat.

2d. I construct the glass holder of brass or other suitable material, in a concave form with three points projecting and inclining toward the burners and elevated to a sufficient height to receive and hold the glass Chimney, with a hole through the centre, three of sufficient size, to receive the screw, made in common form, by means of which the glass holder is made fast to the Dampf.

3^d. Place a glass chimney upon the glass holder, made in the form represented -

If the shade and reflector should be made of tin or other polished metal in the form represented in the annexed drawing with the exterior surface ornamented, & with an opening through the centre to receive the glass chimney over which it is placed, and supported, by means of a metallic holder bent in the form represented in the drawing at 6 in figure A.

For the purpose of exhibiting my said Design I refer
to the annexed drawings thereof

Fig. A represents a stand Lamp with a glass chimney-shade and reflector, ornamented on the exterior surface.

2.2. Two flat tubes

3.3. The projecting parts of the tubes coming in contact with the flame in such a way as to be heated, and serving to melt and keep in a liquid state the hard or other substance to be burned.

4.4.4.4. The openings in the tubes and the wicks.

Fig. C. Represents two round tubes.

1. The screw

2.2. Two round tubes

3.3. The projecting parts as described, in Fig. B.

4.4.4.4. The openings in the tubes where the wicks, may be seen. --

Fig. D. Represents the glass holder.

1. The hole to receive the screw through which the tubes pass.

2.2.2. The projecting points which support the glass chimney.

What I claim as my invention and desire to secure by Letters Patent is the design for a lamp as described in the annexed drawings
